FILAMENT FOR ATTACHING A PRICE TAG TO AN ARTICLE OF MANUFACTURE

Francis G. Merser, Framingham, Mass., assignor to
Dennison Manufacturing Company, Framingham,
Mass., a corporation of Nevada

Filed Apr. 12, 1968, Ser. No. 11,434

Term of patent 14 years

Int. Cl. D20—99; D9—08

U.S. Cl. D96—1

Fig. 1

Fig. 2

Fig. 3

FIG. 1 is a top plan view of a filament for attaching a price tag to an article of manufacture showing my new design, one end being broken away for convenience of illustration;

FIG. 2 is a side elevational view; and

FIG. 3 is a bottom plan view.

I claim:

The ornamental design for a filament for attaching a price tag to an article of manufacture, substantially as shown and described.
